UNITED STATES PATENT OFFICE

CHARLES EDWARD STEVENS AND JOHANNUS CORNELIS SCHOONEMAN, OF ANTWERP, BELGIUM, ASSIGNORS TO INTERNATIONAL STANDARD ELECTRIC CORPORATION, OF NEW YORK, N. Y., A CORPORATION OF DELAWARE

AUTOMATIC TELEPHONE SYSTEM

Application filed September 8, 1930, Serial No. 480,460, and in Great Britain October 9, 1929.

This invention relates to switching arrangements for automatic or semi-automatic telephone systems and more particularly to arrangements of the kind in which selector 5 switches are operated under the control of control or auxiliary switches which are common to a plurality of selector switches.

According to one feature of the invention a control switch common to a plurality of 10 selector switches is adapted to respond to two digits of a wanted number and to cause the advance of a selector switch first to a wanted group of lines and then to a wanted line or subgroup of lines within said selected group 15 under the control of marking potentials applied to marking wires which are connected between the banks of said selector switches and said control switch in such a manner that correct marking is effected in response to 20 both digits without moving the control switch to a predetermined position after the first marking operation has been terminated.

According to another feature of the invention a control switch common to a plurality 25 of conversation selectors is adapted to perform two selective movements, a first to mark a wanted group of lines and a second to mark a wanted line or subgroup of lines in said wanted group, both movements being performed under the control of a mechanism to 30 which the control switch sends revertive impulses.

According to a still further feature a control switch common to a plurality of selector 35 switches is adapted to hunt for a selector switch which has been taken for use and is also adapted to perform the two marking operations specified in the preceding paragraph.

40 The invention is described as applied to a system such as is described in our copending application Ser. No. 370,673, but it is to be understood that the invention is not limited to such arrangements and numerous 45 modifications will readily occur to those versed in the art. It will be evident for example that the invention is equally applicable to circuits using step-by-step switches operated by forward impulses.

50 In the accompanying drawings

Fig. 1 shows a final finder circuit.

Fig. 2 shows a final finder control circuit.

Fig. 3 shows the method of wiring between the final finder switch banks, and the final finder control switch banks.

To make a complete circuit diagram Fig. 2 should be placed beneath Fig. 1.

The arrangement of the bank contacts of the final finder switch, and the final finder control switch as shown in Fig. 3 will first be described.

These switches are of similar construction and have semi-circular banks arranged in levels of 51 points in each.

The upper four levels *e* and *d* shown in the figure are associated with the final finder switch, the two levels *d* being used for P. B. X. hunting and will be described later.

These two levels are wiped over by two single ended brushes set 180° apart, one brush wiping over the lower level during one-half revolution, and the other brush over the upper level during the other half revolution.

The two levels *e* are the line marking contacts a marking potential being applied to one of these contacts in accordance with the position to which the control switch has been set, whereupon the brushes of the final finder are advanced to find this marked contact.

As will be seen the lower level of these two levels contains the marking contacts of the lines 00 to 49, and the upper level the marking contacts of the lines 50 to 99. The brushes are arranged as in levels *d*.

The lower four levels in Figure 3 show the arrangement of the final finder control switch bank.

These control switches serve ten regular final finder switches, and the first ten contacts in the levels *h* and *i* of the control switch bank are wired to these ten final finders for the purpose of allowing the control switch to attach itself to the final finder which has been selected by a preceding group finder switch. The method of wiring is shown clearly in Fig. 2.

The 14th and 15th contacts in the levels *f*, *h* and *i* and every subsequent third and fourth contact in these levels are connected together and are wired to the marking ter-

minals in levels *e* of the final finder switch.

The contacts in levels *f* and *h* are wired to the "tens" marking contacts in level *e* of the final finder switch, and the contacts of level *i* are connected to the units marking contacts in the same level.

The 13th and 14th contact in level *g* and every subsequent third and fourth contact are connected together and grounded. These contacts are the revertive impulse contacts and send the grounded revertive impulses back to the register to count out the digits' trains during the advance of the control switch.

Each of these levels are wiped by single ended brushes which wipe over the contacts one in each half revolution.

The method of wiring as shown in the figure has been developed so as to reduce the time of units selection, and arranged so that when the control switch has to make a maximum number of steps the final finder makes a minimum, and vice versa.

For instance to reach the terminal 99 the brushes of the final finder after reaching the beginning of the tens group have to advance nine steps whereas the control switch advances two steps to mark the ninth terminal in the tens group over brush *i*.

On the other hand to mark the terminal 11, after the final finder has reached the tens group, it is necessary for the control switch to be advanced ten subsequent steps to mark the first terminal in that group. It will be seen therefore that the two switches are arranged to interact to minimize the time of units selection.

The progress of a normal call will now be described.

A free final switch is characterized by a low resistance battery potential on its third wire "C" over a circuit from battery at contact 1 of relay ECR of the final control circuit (Fig. 2), common wire, resistance *R* (Fig. 1). Busy jack BJ of the final switch circuit contact 2 of relay FR1, contact 3 of relay FR3, contact 4 of relay FR2.

A searching preceding group finder such as explained in the copending application referred to will stop due to this low battery potential, and subsequently the fundamental circuit from the register will be extended to the final finder switch, whereupon a battery potential is provided from the register over the "A" wire, contact 2 of relay Fr2, relay *Acr* to ground. Relay *Acr* operates over this circuit and at its contacts operates relay *Ecr* over an obvious circuit. Relay *Acr* at its contact also causes the final control switch to be advanced to find the selected final finder switch over a circuit extending from battery at drive magnet PC of the control switch, contact 1 of relay *Gcr*, contact 5 of relay *Mcr*, contact of relay *Bcr*, contact 3 of relay *Fcr*, contact 1 of relay *Dcr*, to ground at contact

of relay *Acr*. Immediately the switch becomes off normal the off normal contacts are operated in parallel with the contacts of relay *Acr*, to provide holding ground after relay *Acr* has been released.

At contact 1 of relay *Ecr*, the battery marking the "c" wire of all the free final switches associated with the control circuit is disconnected, marking that group busy to all searching group finder switches. This same contact causes the control circuit busy lamp to be illuminated.

Contact 4 of relay *Ecr* prepares the circuit of relay *Bcr* via contact 2 of relay *Fcr*.

The control switch advances until its brush encounters the contact associated with the seized final switch, whereupon the battery or the "A" wire of the fundamental circuit is extended to relay *Bcr*, and thence to ground over the previously described circuit.

Relay *Bcr* at its contacts disconnects the circuit of the control switch drive magnet PC to stop the advance of the control switch, and completes a circuit for relay *Fr1* (Fig. 1) from ground on contact of *Bcr*, wiper and terminal 2 of the control switch, relay *FR1* to battery.

Relay *Fr1* operates and locks over its contacts 2 to the ground on the "C" wire via contact 3 of relay *FR3*, contact 4 of relay *FR2* applied from the preceding switch. At contacts 3 and 4 relay *Fr1* prepares the circuits of relays *Fr3*, and *Ftr*, respectively. At contacts 5 of relay *Fr1* an obvious circuit is closed for the relief relay *Fr4*, this latter relay operates relay *Fcr* at contacts 1, whereupon relay *Bcr* de-energizes.

At contacts 1 of relay *Fr1* a circuit is completed for the outstepping relay in the register and relay *Dcr* in the control circuit over the "B" wire of the fundamental circuit.

Relay *Dcr* operates in this circuit and at contacts 1 recloses the circuit of the control switch drive magnet PC.

The control switch advances until the brush *g* encounters the 1st earthed contact in its lead whereupon a grounded revertive impulse is sent back to the register over the "B" wire via contact 2 of relay *Dcr*, short circuiting the stepping relay therein to count out the tens register. Relay *Dcr* is retained operated by this ground while the brush *g* is passing over the grounded contact.

The control switch continues to advance and at each 3rd and 4th contact sends a revertive impulse back to the register. The numbering scheme is so arranged that the revertive impulses are complementary to a base of 11.

When the tens register switch in the register controller is counted out the fundamental circuit is opened and as soon as brush *g* leaves the grounded contacts relay *Dcr* de-energizes.

At contacts 3 of relay *Gcr* a short cir-

cuit is placed across relay Y_{cr} , the ground on one side of relay Y_{cr} being the initial operating earth of relay G_{cr} the circuit of which has previously been traced, while ground is applied to the other side over contacts 3 of relay G_{ey} , contacts 3 of relay X_{cr} , contacts 2 of relay F_{cr} , contacts 4 of relay E_{cr} to ground. At contacts 4 of relay G_{cr} a circuit is closed for the final finder driver magnet PF , from battery, drive magnet PF , contacts 3 of relay Fr_4 , common wire, contact 4 of relay L_{cr} , contact 1 of relay H_{cr} . A circuit is prepared for relay H_{cr} at contacts 5 of relay G_{cr} , from battery, relay H_{cr} , contact 4 of relay P_{cr} , contact 4 of relay M_{cr} , contact 3 of relay L_{cr} , brush f of the control switch and the contact on which it has been set, thence to a whet the particular tens contact in arc e of the final finder switch.

The brush e of the final finder advances until it encounters this whetted contact, when relay H_{cr} is operated from ground at contact 4 of relay Fr_4 , brush and contact e of the final finder, thence over the circuit previously traced. At contact 1 of relay H_{cr} the circuit for the final finder is disconnected, and a circuit is closed for relay L_{cr} . At contact 3 of L_{cr} a holding circuit is established for relay H_{cr} .

Meanwhile the fundamental circuit from the register has been re-established and relay D_{cr} re-operates.

It will be remembered that relay Y_{cr} was short circuited at contact 1 of relay D_{cr} normal, and when relay D_{cr} operates this short circuit is removed and relay Y_{cr} is allowed to operate in series with relay G_{cr} .

At contacts 2 of relay Y_{cr} an obvious circuit is closed for relay I_{cr} , and at contacts 1 a circuit is prepared for relay M_{cr} . Relay I_{cr} at contacts 1 closes a circuit for relay J_{cr} .

Due to the operation of relay D_{cr} , and provided that the final finder has found the marked tens group, that is, when relay L_{cr} operated, a circuit is closed for PC control switch drive magnet from battery, drive magnet PC , contact 1 of relay L_{cr1} , contacts 5 of relay M_{cr} , contacts 1 of relay D_{cr1} , to ground at the off normal contacts of the switch.

The control switch now starts to rotate from where it was standing after the tens selection, and brush g in passing over the grounded terminals sends back revertive impulses to the register to count out the units train. When the register has counted out the units train and the brush g has passed over the grounded terminal relay D_{cr} de-energizes as before and at contact 1 disconnects the circuit of the drive magnet PC , and connects the circuit for relay M_{cr} , from battery relay M_{cr} , contact 1 of relay Y_{cr} , contact 2 of relay Y_{cr} contacts 3 of relay F_{cr} . Relay M_{cr} looks over its contacts 1 to the ground

at contact 3 of relay E_{cr} , via contact 2 of relay F_{cr} . At contacts 2 and 4 of relay M_{cr} , the relay H_{cr} is connected to the brushes h and i respectively, to whet the selected units contact in the arc e of the final finder.

Unless the first line in a group is the wanted line when relay M_{cr} operated relays H_{cr} and L_{cr} will be released as no ground will be found by the brushes h or i , and the ground at contact 3 of relay L_{cr} locking relay H_{cr} is disconnected at contact 4 of relay M_{cr} . The circuit for the final finder drive magnet is therefore closed over the path previously traced, and the final finder rotates until the brush e encounters the terminal connected with battery via H_{cr} relay. Relay H_{cr} thereupon operates from the ground applied at contact 4 of relay Fr_4 . At contact 1 of relay H_{cr} the circuit for the drive magnet PF is opened, and the circuit for relay L_{cr} is completed as before.

When relay H_{cr} and L_{cr} energized a circuit is completed for relay P_{cr} from battery relay P_{cr} contacts 2 of relay G_{cr} , contacts 1 of relay P_{cr} , contacts 3 of relay M_{cr} , contacts 2 of relay L_{cr} , contacts 1 of relay H_{cr} , over contact 4 of G_{cr} to ground.

Relay P_{cr} is slow to operate and therefore will not operate during the short time interval that its circuit is completed prior to relays H_{cr} and L_{cr} de-energizing and the unit selection commencing. Relay P_{cr} locks over its contacts 1 via contacts 2 of relay G_{cr} . At contact 2 and 4 of relay P_{cr} the circuit of relay H_{cr} via the brush h or i is disconnected, but another circuit is established over contact 4 from the grounded brush d of the final finder via the resistance R_1 and contact 2 of relay Fr_4 . The operating ground for P_{cr} is now extended over its contact 3 of relay P_{cr} , relay X_{cr} to battery. Relay X_{cr} therefore operates and locks to ground over its contact 3, contact 2 of relay F_{cr} , and contact 4 of relay E_{cr} . At contact 3 of Y_{cr} the hold circuit for relays G_{cr} and Y_{cr} is opened.

These relays release and by doing so release relay I_{cr} , and P_{cr} , which in turn release relays H_{cr} , L_{cr} , I_{cr} , and J_{cr} . Relays Y_{cr} , I_{cr} , and J_{cr} , however are slow to release and a considerable time interval will occur before these relays relapse. Relay X_{cr} at contact 1 extends ground over resistance R_3 , contact 4 of relay Fr_1 , relay F_{tr} , to brush c which is resting on the test terminal of the called line. If the called line is free a battery potential is found on the test terminal applied via the cut off relay Cor in the line equipment. Relay F_{tr} operates in series with this. Contact 1 of relay F_{tr} closes an obvious circuit for relay Fr_2 .

Contacts 2 and 3 of relay Fr_2 extend the A and B wires of the fundamental circuit to the called line over the brushes a and b , and disconnect the a wire from the control circuit. At contact 4 the ground on the c wire from

the preceding switch is extended to hold relay F_{tr} and relay Cor , and disconnects the circuit of relay $Fr1$. Relay $Fr1$ does not relapse immediately as a holding circuit is provided over contacts 1 of relay Jcr which being slow to release has not yet relapsed. Contact 1 of relay $Fr2$ opens the circuit of the busy tone the application of which will be described later, and prepares for the application of ringing current to the called line.

When relay Icr finally relapses a ground is passed over its back contact, contact 4 of relay Xcr , contact 3 of relay $Fr1$, relay $Fr3$, to battery. Relay $Fr3$ operates and locks to the ground on the c wire over its contact 4, contacts 1 and 2 of the tripping relay Frr . At contact 1 of relay $Fr3$ the ringing current is applied to the calling line from earth battery source of ringing current, relay Frr , contact 1 of relay $Fr2$. Relay Frr is a marginal relay and will not operate until the called subscriber removes his receiver. Tell tale ringing tone is applied to the calling line through the condenser MFR. Contact 2 of relay $Fr3$ applies a return ground potential for the ringing current.

Relay Jcr now relapses and opens the circuit of relay $Fr1$. Relay $Fr4$ is thereupon released disconnecting the control switch from the final finder. Relay $Fr4$ releases relay Fcr which in turn releases relays Xcr and Mcr . A homing circuit for the control switch is now established from battery at control switch drive magnet PF , contact 1 of relay Gcr , contact 5 of relay Mcr , contact 1 of relay Bcr , contact 3 of relay Fcr , contact 1 of relay Dcr , to ground at the off normal contacts of the switch. The switch will therefore advance until it reaches its home position where the off normal contacts will be broken. Relay Ecr remains operated during this homing operation to maintain the control circuit busy to any searching group finder. When the switch reaches its home position this relay is released freeing the circuit for further use.

Resuming the consideration of a normal call when the called subscriber answers, the current through the relay Frr is increased and this relay operates at contact 1 and 2 of relay Frr , the hold circuit for relay $Fr3$ is opened and this relay releases, and connects the A and B wires through for speaking. The circuit is now connected through with only two relays, Ftr and $Fr2$ operated and locked to the ground on the c wire. At the termination of the conversation, that is when the calling party hangs up his receiver, the ground on the c wire is removed allowing these relays and the cutoff relay in the called parties' line equipment to release and restore the circuit to normal.

If the called line is found engaged a ground will be met on the test terminal of the called line, and consequently relay Ftr is

short circuited and will not operate. When relay Icr relapses ground will be passed over contact 4 of relay Xcr to relay $Fr3$ which operates and locks as before. At contact 1 of relay $Fr3$ a busy tone will be applied to the calling parts from the grounded battery, the secondary winding of the busy tone transformer BT , contact 1 of relay $Fr2$, condenser MRF.

The release of the control circuit occurs as previously explained.

When the calling party hangs up his receiver the ground is removed from the third wire and relay $Fr3$ releases and restores the circuit to normal. The method of P. B. X. grouping will now be explained. It will be seen from a consideration of Fig. 1 that the d terminals of the lines associated with a P. B. X. group are grounded over the normal contacts of their cut-off relays Cor except the last line which is permanently grounded. When a line in a group is engaged the cut-off relay Cor will be operated and therefore the ground will be removed from its particular d terminal.

The final finder under the control of the control switch is advanced to the first line in the required P. B. X. group and if this line is engaged no ground will be found on the associated d terminal. Relays Her and Lcr are operated over the brushes h and i as before, but when Fcr operates due to relay Dcr falling away at the end of the units train no ground is returned from the d terminal over contact 4 of relay Per to hold these relays and they de-energize. A circuit is therefore established for PF final finder drive magnet over contacts 4 of relay Lcr , and contacts 1 of Her , and the switch is advanced until a line is encountered which has a ground on the d terminal, this may be an intermediate disengaged line or the last line which may be either in an engaged or disengaged condition.

The remainder of the call proceeds in a similar manner to a normal call which has previously been described. If it is desired to provide night service on P. B. X. groups, a key NPBR included in the control circuit, when operated, permanently grounds the common wire leading to the d brush of the final finder. This enables each of the P. B. X. trunks to be called as an ordinary line by its individual number.

In the event of a toll call where the ringing current is applied from the toll exchange it is necessary for the relay $Fr3$ to remain inoperative after the required line has been tested and found to be free and relays Ftr and $Fr3$ operated. To accomplish this result the register is so arranged that for a toll call, the fundamental circuit is reclosed for a certain time after the units impulses are finished. Relay Dcr in the control circuit will therefore reoperate previous to the de-energization of relay Icr .

Relay D_{cr} at contact 1 opens the holding circuit for relay F_{r1} , and this relay relapses disconnecting the control circuit previous to the ground being applied to relay F_{r3} at contact 1 of relay $1C_r$ in its normal position.

The A and B wires therefore remain connected through to the toll operator, and allow for the direct passage of ringing.

If the called line is engaged relay F_{r1} remains locked to the c wire, and relay F_{r3} is operated when relay $1C_r$ relapses. Busy tone is thereupon applied to the calling line, and the control circuit is released as previously described.

15 What is claimed is:

1. In a telephone exchange system the combination of a plurality of selector switches, a plurality of lines divided into groups and terminating in contacts of said selector switches, a control switch, means for transmitting digit impulses to said control switch, means under control of said control switch in response to two digit impulses to cause one of said selector switches to advance, first to a group of lines and then to a line within said group, comprising electrical connections between contacts in the selector switch and said control switch to which marking potentials are applied.

20 2. In a telephone exchange system the combination of a plurality of selector switches, a plurality of lines divided into groups and terminating in contacts of said selector switches, a control switch, means for transmitting digit impulses to said control switch, means under control of said control switch in response to two digit impulses to cause one of said selector switches to advance, first to a group of lines and then to a line within said group, the means under control of said control switch comprising electrical connections between contacts in the selector switch and said control switch to which marking potentials are applied, without moving said control switch to a predetermined position after the first marking operation has terminated.

25 3. In a telephone exchange system the combination of a plurality of final selector switches provided with banks, a control circuit including an auxiliary switch, means for transmitting tens and units digits impulses to said switch, and means controlled by said control circuit and auxiliary switch in response to the tens and units digit impulses to successively perform two marking operations in the bank of a selector switch.

40 4. In a telephone exchange system the combination of a plurality of final selector switches provided with banks, a control circuit including an auxiliary switch, means for transmitting tens and units digit impulses to said switch, and means controlled by said control circuit and auxiliary switch in response to the tens and units digit impulses to successively perform two marking

operations in the bank of a selector switch, without advancing to an intermediate or normal position between said two marking operations.

5. In a telephone exchange system the combination of a plurality of selector switches provided with banks to which groups of lines are connected, a control switch common to a plurality of said selector switches, said control switch having two selective movements, a control mechanism, means controlled by said control switch to first mark a group of lines in the banks of a selector and then mark a particular line in the group, means controlled by said mechanism for controlling the selective movements of said control switch, and means controlled by said control switch to send revertive impulses to said mechanism.

70 6. In a telephone exchange system the combination of a plurality of selector switches, banks for said switches connected with groups of lines, a control circuit common to said selector switches and provided with a control switch, means for associating said control circuit with any one of said selector switches, means for advancing said control switch to mark a group of lines in the bank of a selector switch, means for advancing said selector switch to the group of marked lines, means for advancing said control switch to mark a particular line in the group, and means for then advancing said selector switch to said marked line.

75 7. In a telephone exchange system the combination of a plurality of selector switches, banks for said switches connected with groups of lines, a control circuit common to said selector switches and provided with a control switch, means for associating said control circuit with any one of said selector switches, means for advancing said control switch to mark a group of lines in the bank of a selector switch, means for advancing said selector switch to the group of marked lines, means for advancing said control switch to mark a particular line in the group, means for then advancing said selector switch to said marked line.

80 8. In a telephone exchange system the combination of a plurality of selector switches provided with banks connected to a group of lines, a control circuit common to said selector switches and provided with a control switch, means for causing said control switch to select a selector switch, and means for then causing said control switch to first mark a group of lines in the bank of the selected selector switch and then to mark a particular line in said group.

85 9. In a telephone exchange system the combination of a plurality of selector switches provided with banks connected to a group

of lines, a control circuit common to said selector switches and provided with a control switch, means for causing said control switch to select a selector switch, means for causing said control switch to first mark a group of lines in the bank of the selected selector switch and then to mark a particular line in said group and means for controlling the marking operations of said control switch comprising a mechanism to which the control switch sends revertive impulses.

10. In a telephone exchange system the combination of a plurality of selector switches provided with banks connected to a group of lines, a control circuit common to said selector switches and provided with a control switch, means for causing said control switch to select a selector switch, means for causing said control switch to first mark a group of lines in the bank of the selected selector switch and then to mark a particular line in said group, said control switch provided with a brush and a bank of grounded contacts, the means for controlling the marking operations of said control switch comprising a mechanism to which revertive impulses are sent from said brush and contacts.

11. In a telephone exchange system the combination of a plurality of selector switches each provided with a relay, a control circuit provided with an auxiliary switch, said control circuit connected in multiple relation to said selector switches, means for causing the operation of said auxiliary switch to select one of said selector switches, said selector switch when selected causing the operation of one of said relays, the operation of said relay serving to connect said control circuit with the selected selector switch.

12. In a telephone exchange system the combination of a selector switch having access to a group of lines, said selector switch provided with bank contacts, each contact being normally connected to ground, a driving magnet for said selector switch, a line relay for each of said lines, a control circuit common to said selector switch, means for operating said relays, the operation of said relays serving to remove ground from the bank contacts and the removal of said ground causing the operation of said control circuit to reoperate the driving magnet of the selector switch.

13. In a telephone exchange system the combination of a selector switch provided with bank contacts, an auxiliary switch also provided with bank contacts, connections extending between the bank contacts of said switches, means for causing said auxiliary switch to make two movements, the first movement causing the selector switch to advance to a group of contacts and the second movement causing the selector switch to ad-

vance to a contact in the group, the connections between the bank contacts of the two switches being such that when the control switch makes a maximum movement during its second movement the selector switch makes a minimum movement and vice versa.

14. In a telephone exchange system the combination of a plurality of selector switches for selecting groups of lines, a control switch common to said selector switches, means for transmitting two digit impulses to cause the operation of said control switch, means under control of said control switch for causing said selector switches to first advance to select a group of lines corresponding to the first digit and to a line in the group corresponding to the second digit.

15. In a telephone exchange system the combination of a plurality of conversation switches for selecting groups of lines, a control switch common to said conversation switches and having two selective movements, means controlled by said control switch in its first movement to cause said conversation switches to select a group of lines and in response to the second movement to select a line in the group.

16. In a telephone exchange system the combination of a plurality of conversation switches for selecting groups of lines, a control switch common to said conversation switches and having two selective movements, means controlled by said control switch in its first movement to cause said conversation switches to select a group of lines and in response to the second movement to select a line in the group, a mechanism for controlling both selective movements of said control switch, and means controlled by said control switch for sending revertive impulses to said mechanism.

17. In an automatic telephone system a selector switch having a bank of contacts and wipers adapted to engage with said contacts, an auxiliary switch having a bank of contacts and wipers adapted to engage with said contacts, electrical connections extending between contacts of said auxiliary switch and certain contacts representing the tens groups of said selector switch and other electrical connections extending between contacts of said auxiliary switch and contacts of said selector switch intermediate said certain contacts and representing the units in said tens groups, means for successively moving the wipers of said auxiliary switch in accordance with tens and unit digits and means for moving the wipers of said selector switch into engagement with its bank contact which has been marked by the electrical connections from the auxiliary switch.

18. In a telephone system the combination of a selector switch, an auxiliary switch associated with said selector switch, a plurality of marking wires connecting the bank ter-

5 minals of said selector switch and said auxiliary switch whereof each marking wire extending from a tens group contact in the bank of said selector switch is connected to a plurality of contacts in the bank of said auxiliary switch whereas the units marking wires extending from single contacts in the bank of the auxiliary switch are connected to a plurality of units contacts in the bank of 10 said selector switch, means for operating said auxiliary switch in accordance with tens and units digit impulses to mark a contact in the bank of said selector switch and means for driving the brushes of said selector switch to said marked contact.

15 19. In a telephone system the combination of a selector switch, an auxiliary switch associated with said selector switch, a plurality of marking wires connecting the bank terminals of said selector switch and said auxiliary switch, individual lines and groups of 20 private branch exchange lines connected to the bank of said selector switch, means for operating said auxiliary switch in accordance with tens and units digit impulses to mark 25 a contact in the bank of said selector switch, means for driving the brushes of said selector switch to said marked contact and means operative if said marked contact is a busy 30 first line of one of said groups of private branch exchange lines to cause said driving means to drive said brushes over said group of private branch exchange lines to select a free line within the group.

35 20. A telephone system according to claim 19 and wherein said auxiliary switch forms part of a control circuit common to a plurality of said selector switches, characterized in this that the cut-off relays of the private 40 branch exchange lines except the last line of each group are adapted when energized to remove the ground from a contact in the bank of the selector switch, the absence of such ground being adapted to effect an operation 45 in said control circuit to cause the reclosure of the circuit of the driving magnet of the selector switch.

21. In a telephone exchange system the 50 combination of a plurality of selector switches, means for busying one of said switches, a control switch common to said selector switches, a plurality of marking wires connecting bank terminals of said selector switches and said control switch, means for causing said 55 control switch to select the said busy selector switch, and means for causing the said control switch to make a plurality of selective movements to control the said selector switch by marking potentials applied over said 60 marking wires.

22. In a telephone exchange system the 65 combination of a plurality of selector switches, a plurality of auxiliary control switches less in number than said selector switch and each common to a group of said selector

switches, marking wires connecting the bank terminals of said control switches and the bank terminals of the selector switches in the respective groups, driving means common to all of said switches, means for operatively 70 connecting any of said switches with said common driving means, means for controlling the movement of said control switches in accordance with the value of received digit impulses, and means for controlling the movement of said selector switches by marking potentials applied over said marking wires. 75

In witness whereof, we hereunto subscribe our names this 19 day of August 1930.

CHARLES EDWARD STEVENS. 80

JOHANNUS CORNELIS SCHOONEMAN.
